ELECTROSTATIC COATING METHOD AND APPARATUS

Daniel S. Gustin and Albert W. Wainio, Bloomfield, N. J., assignors to Westinghouse Electric Corporation, East Pittsburgh, Pa., a corporation of Pennsylvania

Application May 30, 1945, Serial No. 596,728

3 Claims. (Cl. 117—33.5)

1

The present invention relates to the coating of vitreous material and has particular reference to a method and apparatus for applying a fluorescent coating to the envelope of a fluorescent lamp and constitutes a continuation-in-part of our application, Serial No. 487,578, filed May 19, 1943 and now abandoned.

At the present time the customary method of coating fluorescent lamps is to suspend the fluorescent powders in a highly volatile binder and flush the inside of the envelope with the solution thus formed. The coated envelope or container is then allowed to dry for a short period, after which it is heated to a temperature sufficiently high to carbonize and drive off the binder.

The difficulty with prior art methods resides in the fact that the lamp envelope or container must be handled several times, and since they are heated to a comparatively high temperature to volatilize the binder, an extensive cooling period is required before sealing-in the electrodes and completing the finished lamp. In addition, and more significantly, the firing of the coated container to drive off the binder affects the color characteristic of the finished lamp. Actual tests have shown that any given fluorescent material, when subjected to ultra-violet radiations, will become excited with a great deal more brilliance or intensity than after applied to a container by a binder, the latter of which is subsequently driven off by volatilization.

Perhaps the explanation for this may be that a molecular layer of the binder remains beneath the particles of the fluorescent material after firing which is not removed, or such layer obtains insufficient oxygen during the firing step to completely carbonize and burn off, thus leaving a minute charred surface beneath the fluorescent particles. Whatever the explanation, the fact remains that either the fluorescent material is not excited by the ultra-violet to as high an intensity or a minute charred surface absorbs some of the visible light, preventing it from getting out of the envelope, thus materially decreasing the efficiency of the lamp.

A further requisite of fluorescent lamps of high efficiency is that the coating must be applied uniformly. In other words, it is not only essential that the coating be of a uniform thickness throughout the envelope, but it must be uniform as possible from the standpoint of particle distribution. Since the visible light generated by the coating under excitation by ultra-violet must be transmitted through the vitreous envelope, the particles must not be disposed too thick nor ag-

glomerated, for otherwise the visible light will be absorbed by the under layers of particles. On the other hand, the coating must not be too thin as this would not provide sufficient particles for excitation by the ultra-violet and conversion into visible light, resulting in waste of the invisible ultra-violet and a very inefficient source of visible light.

It is accordingly an object of the present invention to provide a method for coating the surface of a container for a fluorescent lamp which is exceedingly economical to apply.

Another object of the present invention is the provision of a method of coating a container for a fluorescent lamp wherein the fluorescence of the coating under excitation by ultra-violet radiations is in no way impaired.

Another object of the present invention is the provision of apparatus for applying a uniform coating of fluorescent material to the container for a fluorescent lamp and wherein no binder is required to form a tenacious bond between the fluorescent material and the container.

Another object of the present invention is the provision of an apparatus for electrostatically precipitating dry fluorescent powder on the wall of a container for a fluorescent lamp to form a uniform coating thereon.

A further object of the present invention is the method of coating a container for a fluorescent lamp which is electrostatically applied by precipitation from an aeroform suspension and then slightly wetted by a volatile moistening material to settle the particles on the container wall.

Still further objects of the present invention will become obvious to those skilled in the art by reference to the accompanying drawing wherein:

Fig. 1 is an elevational view partly in section of an apparatus for the coating of a container for a fluorescent lamp in accordance with the present invention;

Fig. 2 is a cross-sectional view taken on the line II—II of Fig. 1;

Fig. 3 is an enlarged sectional view of a part of the apparatus shown in Fig. 1;

Fig. 4 is an elevational view partly in cross section and partly fragmentary and illustrating a fluorescent lamp during the steam setting step;

Fig. 5 is a fragmentary view of a completed fluorescent lamp in accordance with the present invention;

Fig. 6 is a fragmentary view on an enlarged scale of a section of the lamp envelope showing the pattern of the coating particles when applied

to the envelope while the latter is heated to the upper end of the temperature range;

Fig. 7 is a fragmentary view on an enlarged scale of a section of the lamp envelope showing the more uniform pattern formed by the coating particles when the envelope is heated to the most desirable temperature.

Fig. 8 is a microphotographic cross-sectional view of seventy-five times magnification of an envelope having an electrostatically applied coating thereon;

Fig. 9 is a cross-sectional view identical to that of Fig. 8 but showing the cross-section of the electrostatically applied coating following treatment with a volatile moistening fluid or vapor in accordance with the present invention;

Fig. 10 is a microphotographic view of seventy-five times magnification of the surface of an electrostatically applied coating to the container for a fluorescent lamp and illustrating reflected light by the coating;

Fig. 11 is a surface view identical to that of Fig. 10 but showing the reflected light from the electrostatically applied coating following treatment with a volatile moistening fluid or vapor in accordance with the present invention;

Fig. 12 is a microphotographic view of seventy-five times magnification of the surface of an electrostatically applied coating to the container for a fluorescent lamp and illustrating transmitted light through the coated container wall, and;

Fig. 13 is a surface view identical to that of Fig. 12 but showing the transmitted light through the electrostatically coated container wall following treatment with a volatile moistening fluid or vapor in accordance with the present invention;

Fig. 14 is a microphotographic view of seventy-five times magnification of the surface of a coated container which was coated by the well known flush method and showing the amount of reflected light;

Fig. 15 is a surface view identical to that of Fig. 14 but showing the amount of transmitted light through a container coated by the prior art flush method.

Referring now to the drawing in detail, the apparatus as shown in Fig. 1 comprises a base 5 which may be supported above the floor by legs 6. Disposed near one end of the base is a retort or reservoir 7 of vitreous material such as glass, metal or the like, which for convenience will be herein referred to as the smoke generator. The purpose of this smoke generator is, as the name implies, to convert the fluorescent powder into an aeriform suspension or "smoke." By this is meant a cloud of finely divided particles from which heavier particles have been filtered such as by gravitation in a reservoir or the like. Moreover, such "smoke" is formed by means of an air jet mixing air with the powder under just sufficient pressure to cause the smoke to drift through a reservoir and out of an outlet or extension into the container to be coated. Although the air pressure controls to some extent the thickness of the applied coating by affecting the density of the smoke, the pressure is not so high as to impart velocity to the suspended particles in a direction other than their drift as this would produce agglomerates and a too thick non-uniform coating. On the contrary, and as hereinafter explained, the coating is applied to the interior wall of the container solely by ionization and precipitation of the smoke without any

velocity component imparted to the particles during precipitation by the gaseous medium.

To accomplish this, the fluorescent powder 8 is inserted into the reservoir 7 after having been ground to a very fine mesh. Naturally, the particular fluorescent material will vary depending upon the color of the light desired when the material is excited by ultra-violet radiation. For example, if a blue lamp is desired, calcium tungstate activated with lead may be employed; while for white light, a mixture of magnesium tungstate activated with thoria and zinc beryllium silicate activated with manganese may be used. As will be noted, the reservoir is provided with an outlet 9 at the bottom thereof and through which the powder 8 is fed at a uniform rate by a worm feed 10 affixed to a shaft 12 extending through the reservoir and journaled in a stopper bearing 13 at the top of the reservoir 7.

In order to rotate the worm feed 10 and shaft 12 at a relatively slow speed, the latter is provided with a pulley 14, connected by a belt 15 passing over bracket supported idler pulleys 16, to a pulley 17. This pulley 17 is carried by a shaft extending from a reduction gear box 18 and this gear train is driven by an electric motor 19. The outlet 9 of the reservoir 7 communicates with an annular passage or mixing chamber 20 provided with a jet 22 through which a gaseous medium under pressure, such as air or the like, is admitted from a conduit 23 by control of a valve 24. A conduit 25 also communicates with the chamber 20 and with approximately the center of the reservoir 7 with the result that the gaseous medium, in flowing under pressure through the mixing chamber 20, sucks the finely divided powder 8 along with it, whereby it is blown into the reservoir 7 in the form of a comparatively dense smoke 26, the heavy fluorescent particles gravitating to the bottom of the reservoir 7, to be again fed through the outlet 9 by the worm feed 10.

A smoke outlet in the form of an extension 30 is provided in the reservoir 7 which is supported by a bracket 32 extending upwardly from the base 5 for the purpose of forcing the smoke under pressure into the container to be coated. The container or envelope 33 for a fluorescent lamp which is to be coated with the fluorescent material is arranged to be supported upon a pair of rollers 34 and 35, shown more clearly in Fig. 2. These rollers are carried by shafts 36 journaled in the bracket 32 as well as in a similar bracket 37, and in order to maintain the rollers in a desired position against the action of contraction and expansion thereof coil springs 38 bear against one end of the rollers 34, 35 and the bracket 37.

For the purpose of rotating the rollers 34 and 35, as well as the vitreous container 33 which frictionally engages the rollers, a second reduction gear train 39 driven by an electric motor 40 is supported by the base 5. By reference now more particularly to Fig. 2, it will be noted that the driven gear 42 of the gear train 39 meshes with a gear 43 affixed to the shaft 36 carrying the roller 34. An idler gear 44 is pivotally secured to the bracket 32 which meshes with the gear 43 and also with a similar gear 45 carried by the shaft 36 supporting the other roller 35 so that the latter is rotated in the same direction as the roller 34. A gas burner 46 provided with a plurality of jets 47 is positioned longitudinally of the rollers 34, 35 and container 33, so that the latter may be heated during rotation by the

gas flames passing upwardly between the rollers, as shown in Fig. 2, with such burner connected to a conduit 48 leading to a source of gaseous fuel supply.

The temperature to which the container is subjected has been found to be important. Not only does heating of the container change it from an electrically insulated body to an electrically conducting container serving as an electrode as hereinafter described, but the temperature also determines the pattern assumed by the coating particles. It has been found that the temperature limits for good coatings are not abrupt but range from about 175° C. to about 400° C. However, heating the container to a temperature near the upper limit of the range at 350° C. produces a coating progressively rougher with higher container temperatures, with the coating particles seemingly looser and building themselves into small mounds not conducive to efficiency such as shown in Fig. 6. At temperatures near the lower limit of the range, the coating particles form designs or patterns which become larger and more pronounced as the temperature of the container is reduced to room temperature. The most uniform coating, such as shown in Fig. 7, is obtained at about 200° C., which is the desirable temperature for the container.

Referring again to Fig. 1, it will be noted that the smoke outlet 30 from the smoke generator aligns coaxially with the container 33 when in position upon the rollers 34 and 35 so that the fluorescent material smoke is passed into the container. In order to accommodate containers of varying length, small tubular pieces of vitreous material or the like 49 are shown positioned at each end of the container to thus act as temporary extensions of the latter, and a suitable gasket or the like 50 is positioned between the tubular extension 49 and the bracket 32 to prevent the escape of smoke, thereby causing it to pass through the tubular extension into the container 33.

The finely divided fluorescent powder thus suspended in the air in the form of smoke is then ionized and electrostatically precipitated onto the inner surface of the container. A high voltage direct current generator 52 which generates a current ranging from 30 to 50 microamperes at a voltage of from 5000 to 15,000 volts is carried by the base 5. This generator may be of any suitable type, but it has been found convenient to employ a power pack comprising a transformer together with suitable rectifier tubes which will give the desired D. C. output energy, and since the generator per se forms no part of the present invention, it is believed unnecessary that it be further herein described in detail. It should suffice to say that one side of the generator is grounded as shown at 53 to the metallic parts of the apparatus, while the other side is connected to an insulated terminal 54 supported by an upwardly extending bracket 55 from the base 5.

This bracket 55 also serves as one insulated bearing for an elongated electrode 56 provided with a sharp pointed end 57 and which is further supported by an additional insulated bearing 58 likewise supported by a bracket 59 extending upwardly from the base 5. Electrical connection is made from the insulated terminal 54 to the electrode 56 by means of a brush contact 60 so that only the electrode 56 is at one polarity, while all other metal parts of the apparatus are at opposite polarity due to the ground connection 53.

The electrode 56 is moved so that its sharpened

end 57 passes longitudinally and coaxially of the container 33 by a mechanism comprising a rack-bar 62 having an angular projection 63 to which one end of the electrode 56 is secured. This angular projection is supported by small rollers or casters 64 engaging a track 65 secured to the base 5, and the rack-bar 62 meshes with a small gear 66 affixed to a shaft 67 journalled to an up-standing bracket 68. A large pulley 69, also connected to the shaft 67, is rotated by a reversible electric motor 70 and belt connection 72. Suitable limit switches 73 are provided which are adapted to be engaged by adjustable projections 74 carried by the angular rack-bar projection 63 so as to stop the electrical motor 70 when the sharpened end 57 of the electrode 56 has reached its limit of travel.

In practicing the method of the present invention, the apparatus above described is operated in the following manner. The container 33 to be coated is first placed upon the rollers 34 and 35 in direct communication with the outlet 30 of the smoke generator 1, either with or without the tubular extension 49 as required, and motor 70 started by the operator closing a control switch 75, thus causing rotation of the rollers 34 and 35 as well as the container 33 in the direction indicated by the arrows in Fig. 2. The gas jets 47 are then lighted to heat the container and the operator closes a reversing switch 76 to start the motor 70 so as to cause movement of the rack-bar 62 and electrode 56 to the right as shown in Fig. 1. This accordingly causes the electrode 56 to slide through the insulated supported bearings carried by the brackets 55 and 59 until the sharpened electrode end 57 reaches the farthest end of the container 33, as shown in Fig. 1, at which time the projection 74 will engage the limit switch 73 to stop the electric motor 70.

The electric motor 19 is then started by closure of a switch 77 which thus rotates the worm feed 16, forcing the finely divided fluorescent powder within the reservoir 7 through the outlet 9. The valve 24 is then opened, allowing the air or gas under pressure to pass through the chamber 20 where it sucks up the fluorescent powder, thus suspending it in the air in the form of smoke which is exhausted through conduit 25 into the reservoir 1. This smoke then passes out of the reservoir 7 through the outlet 30, and since the latter is in direct communication with the vitreous container 33 either with or without the tubular extensions 49, the smoke passes into the container with leakage thereof being prevented by the gasket 50.

The operator next closes a switch 78 to connect the high voltage D. C. generator 52 to a source of electrical energy of the customary domestic potential of about 115 volts, which accordingly impresses a high D. C. voltage between the electrodes 56 and all metal parts of the apparatus. Also, since the gas flames are ionized, they form suitable electrodes for contacting the vitreous container 33 which, being hot, is rendered semi-conducting, not only by the gas flames, but by virtue of its contact with the metal rollers 34 and 35, thus impressing the high voltage across the vitreous container as one electrode and the axially disposed elongated electrode 56.

The motor 70 is again started by closure of the reversing switch 76 so as to withdraw the electrode 56 from within the container 33. As the sharpened end 57 is moved relatively slowly, the high voltage impressed between the electrode 56

and the vitreous container 33 ionizes the fluorescent powder 26 suspended in the air, thus causing a discharge, and the resulting high electrostatic field at the sharpened electrode end 57 precipitates the minute fluorescent particles onto the inner surface of the heated container, forming an exceptionally uniform layer. Precipitation of the fluorescent material follows the sharpened electrode end 57 as it moves along the axis of the container 33 until the electrode end is completely withdrawn from the container, at which time the projection 74 carried by the angular portion 63 of the rack-bar 62 will engage the other limit switch 73 to again stop the electric motor 70.

In describing the operation of the apparatus in the manner above noted, it should be understood that the coating can be just as readily applied by the high electrostatic field generated and during movement of the electrode 56 into the container 33 in the same manner as described relative to movement of the electrode 56 out of the container. However, it is preferable to coat the container only during outward movement of the electrode 56 since obviously the electrode must be outside of the container in order to remove the latter from the rollers. In order to save time so as to coat envelopes during either direction of movement of the electrode 56, the smoke generator can be made so that it detachably connects to the container and pivots about an axis so as to allow withdrawal of the container from the electrode if desired.

It sometimes happens that in a fluorescent lamp coated by the foregoing electrostatic method, the liquid mercury often dislodges part of the coating, either by the free mercury rolling about and producing streaks in the coating or by sudden impact and splattering of the mercury, causing the coating to be torn off in a characteristic ring shape.

To obviate this disadvantage, it was found that, by passing a suitable moistening material or agent through the electrostatically-coated fluorescent envelope and condensing or volatilizing out, upon subsequent drying either in air or by application of heat to hasten drying, the coating is much tougher, adheres more tenaciously, and resists mechanical injury from the mercury. Such moistening material or agent may be a highly volatile fluid such as alcohol, acetone, or a readily condensable rapid drying vapor such as steam mixed with air, which is flushed through the electrostatically coated container.

Although no confirmation of the theory as to why moistening the electrostatically applied coating imparts toughness and greater tenacity thereto has yet been made, it is believed due to the fact that after application of the particles to the container wall, such as shown particularly in Fig. 8, the passing of the moistening material or agent into the container wets the particles to a slight degree. Upon volatilization or condensing out of the moistening material or agent, and subsequent drying as above mentioned, there apparently results an expansion and contraction of the particles which increases their surface tension, causing more tenacious adherence.

Whatever the explanation, the fact remains that the electrostatically coated fluorescent lamp can withstand heavy impacts after this latter treatment without the particles in any way being dislodged or effected by free mercury, while before this moistening treatment slight jarring quite readily loosened the particles.

Moreover, the treated coating has an entirely

different surface which is apparent, not only from the standpoint of compactness and smooth surface, as shown by the comparison between the untreated cross-sectional view of Fig. 8 with the treated cross-sectional view of Fig. 9, but also from Figs. 10 and 11. For example, in Fig. 10 it will be noted that the light reflected by the surface of the unmoistened electrostatically applied coating is far from uniform. Moreover, the coating has no definite pattern but a few isolated aggregates or agglomerates with the majority of the granules apparently being flattened or end-wise and reflect very little light.

A comparison, however, with the moistened and dried electrostatically applied coating of Fig. 11 clearly shows that it is orientated and forms a continuous systematic network or interlocking of granule aggregates or agglomerates extending over substantially the entire surface, thus reflecting light from substantially the entire surface. Since a fluorescent lamp for best efficiency must reflect as well as transmit light, it can be seen from Fig. 11 that the efficiency is greatly enhanced by the increase of reflected light by the treated coating.

The treatment of the electrostatically applied coating in accordance with the present invention also greatly increases the amount of transmitted light which is naturally a further requisite of an efficient fluorescent lamp. This can be seen from a comparison between Figs. 12 and 13 wherein very little light is transmitted through the untreated coating of Fig. 12 as can be observed from the extremely few white spots therein shown. Since the untreated coating is less compact, this may be due to scattering of the radiation among the coating granules or particles. In Fig. 13, however, the transmitted light is distributed like the reflected light, over substantially the entire surface much in the same form or orientated network of the agglomerates. This would appear to indicate there is less scattering of radiation by the particles, but regardless of the explanation, it is obvious from Fig. 13 that the transmitted light is greatly increased.

It can accordingly be readily seen from Figs. 11 and 13 that the orientated systematic interlocking network of particle agglomerates formed by the treatment of the present invention increases both the reflected and transmitted light with an attendant increase in efficiency of the fluorescent lamp and at the same time produces a tougher and more tenacious coating as above noted.

Moreover, by comparing the amount of both reflected and transmitted light from a fluorescent lamp coated by the method of the present invention with that of a lamp coated by the well known prior art flush method, as can be seen from Figs. 14 and 15, it is obvious not only that the coating agglomerates are of an entirely different formation, but that the reflected and transmitted light resulting from the coating of the present invention is greatly increased over that of the flush coated fluorescent lamp.

Accordingly, upon complete coating of the container or envelope 33, it is removed from the apparatus of Fig. 1 and inserted in the treating apparatus as shown in Fig. 4, which may form a part of the same machine or be separate therefrom, as desired. This apparatus as shown comprises a base member 80 having a spring-clip fastener 82 projecting therefrom, as well as a metallic fitting 83. Although a plurality of such devices may be provided so that numerous lamps 75 may be treated simultaneously, for the sake of

simplicity only one has been shown. Although, as above noted, the moistening agent or material may be a volatile fluid or steam, the apparatus has been illustrated as utilizing steam and air although any of the above agents can be just as readily utilized with the apparatus. A passageway 84 extends longitudinally of the fitting and is provided at the bottom with a drain cock 85, while at the top a threaded bushing 86 and gasket 87 is provided to form a fluid-tight connection with the container 33 when the latter is inserted in the spring-clip 82.

A Y-connection 88 having branches 89 and 90 communicates with the passageway 84 and with a source of low pressure air and a steam source, through manipulation of respective valves 92 and 93. By operation of these valves, steam, together with low pressure air in the proper proportion, is introduced through the passageway 84 and upwardly through the envelope 33. By proper mixture of the steam and air, the distribution of moisture will be substantially uniform from one end of the envelope 33 to the other without the formation of water droplets which might mar the coating.

There is, however, for every different percentage mixture of air and steam (water vapor) a certain dew-point temperature above which liquid water will not condense from the mixture, but below which it will condense. Also, the lower the percentage of steam in the air, the lower the dew-point temperature will be. Therefore, if the envelopes are essentially at the same temperature throughout their length, on passing the air-steam mixture through them, each section of each envelope will condense moisture and thus be heated by the latent heat of condensation of water. Just as soon as enough water has condensed to raise the temperature of the lower section of the envelope to the dew-point, no more moisture will condense on this section and the air-steam mixture will pass on by, condensing on the upper section of the envelope until the same dew-point is reached and the same quantity of water has condensed per unit area of the envelope. The envelopes are then allowed to dry by passing air therethrough by closing of the steam valve 93, or they may be removed from the steaming apparatus and heated to more quickly dry them, if desired.

This steaming step fixes the coating so that it is more tenacious and resistant to mechanical injury from the mercury as before mentioned, thus conditioning the envelope for fabrication into a completed lamp 94 as shown in Fig. 5. The filamentary electrodes 95 and 96 are sealed into the ends of the envelope in the manner well known in the art, and after evacuation the lamp is filled with a gaseous medium, such as argon, neon or a mixture thereof, together with a small quantity of mercury. By reference to Fig. 5 and to the microphotographic views of Figs. 9, 11 and 13, it will be seen that the fluorescent particles form an adhesive bond with the interior envelope wall and there is an entire absence of any intervening layer of foreign material which would otherwise impair the visible light given off by the fluorescent material under excitation by the ultra-violet radiations.

It will thus become obvious to those skilled in the art that a method and apparatus is provided by the present invention which enables the electrostatic precipitation of dry fluorescent powders directly onto the glass bulb or container for a fluorescent lamp from a cloud of smoke. More-

over, since the coating is applied while the container is hot, it is possible to combine the coating operation with glass tube making machines in such manner that the glass never becomes cold from the time it is drawn until after it is completely coated. It is also significant that since the coating particles are ionized and precipitated from a cloud of smoke, a uniform coating both in thickness and particle distribution and size is obtained as no velocity component is imparted to the particles by fluid pressure during precipitation. Inasmuch as no binder is required but the material is fixed by a moistening treatment, a closer tenacious coating results with the inherent fluorescent properties of the material being in no way impaired, thus not only increasing the efficiency of the light output from the completed fluorescent lamp, but also producing an entirely different color of the light from that of a lamp in which a binder is used. A further economy resulting from the method of the present invention resides in the fact that substantially all of the fluorescent material is used and none is lost.

Although one specific embodiment of the present invention has been shown and described, it is to be understood that still further modifications thereof may be made without departing from the spirit and scope of the appended claims.

We claim:

- 30 1. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles and deviation thereof from their normal direction of drift with attendant coating of the envelope walls solely by precipitation of such particles, and passing a readily condensable vapor which does not decompose the coating material into the envelope over the precoated surface thereof, and subsequently drying the same to make the particles adhere more tenaciously to the envelope.
- 35 2. The method of forming a uniform coating of a stable fluorescent material on the inner surface of the vitreous envelope for a fluorescent lamp which comprises generating the smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles, and deviation thereof from their normal direction of drift with attendant coating of the envelope wall solely by precipitation of such particles, and passing steam and air into the envelope over the pre-coated surface thereof, and subsequently drying the same to make the particles adhere more tenaciously to the envelope.
- 40 3. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles and deviation thereof from their normal direction of drift
- 45 4. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles and deviation thereof from their normal direction of drift
- 50 5. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles, and deviation thereof from their normal direction of drift with attendant coating of the envelope wall solely by precipitation of such particles, and passing steam and air into the envelope over the pre-coated surface thereof, and subsequently drying the same to make the particles adhere more tenaciously to the envelope.
- 55 6. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles, and deviation thereof from their normal direction of drift with attendant coating of the envelope wall solely by precipitation of such particles, and passing steam and air into the envelope over the pre-coated surface thereof, and subsequently drying the same to make the particles adhere more tenaciously to the envelope.
- 60 7. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles and deviation thereof from their normal direction of drift
- 65 8. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles and deviation thereof from their normal direction of drift
- 70 9. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles and deviation thereof from their normal direction of drift
- 75 10. The method of forming a uniform coating of a stable fluorescent material on the inner surface of the vitreous envelope for a fluorescent lamp which comprises generating a smoke by suspending finely divided fluorescent powder in a gaseous medium, applying a slight pressure to the smoke to cause it to drift into the envelope in substantially a definite direction, subjecting the smoke to a high electrostatic field to cause ionization of the suspended particles and deviation thereof from their normal direction of drift

11

with attendant coating of the envelope wall solely by precipitation of such particles, and passing a volatile fluid which does not decompose the coating into the envelope over the precoated surface thereof, and subsequently drying the same to make the particles adhere more tenaciously to the envelope.

DANIEL S. GUSTIN.
ALBERT W. WAINIO.
